ASSIGNORS TO ENGINEER'S SPECIALTY MANUFACTURING COMPANY, OF SCRANTON,
PENNSYLVANIA, A CORPORATION OF PENNSYLVANIA.

LUBRICATOR.

1,168,508.

Specification of Letters Patent.

Patented Jan. 18, 1916.

Application filed August 10, 1915. Serial No. 44,807.

To all whom it may concern:

Be it known that we, EDWARD A. JONES and JOHN E. JONES, citizens of the United States, residing at Scranton and Throop, respectively, in the county of Lackawanna and State of Pennsylvania, have invented certain new and useful Improvements in Lubricators, of which the following is a specification.

10 This invention relates to new and useful improvements in automatic lubricators, the object of the invention being the provision of a lubricator for feeding graphite or any lubricants manufactured in solid form to the 15 valves of steam engines, pistons of engines or any other moving parts for which such lubricant may be intended.

20 A further object of this invention is the construction of a lubricator by means of which stick graphite may be exposed to the action of a reciprocating cutter and the part 25 of the graphite thus shaved off mixed with steam supplied to the lubricator and the mixed graphite and steam fed from the lubricator to the parts being lubricated.

30 A still further object of the invention is the provision of a steam jet to the lubricator in such a manner that any steam pressure in the lubricator will not tend to hold the stick 35 of graphite out of engagement with the cutter mechanism.

35 In many instances, it is advisable to also supply a certain proportion of the oil to the graphite and steam and this invention comprehends the provision of means by which an oil cup may be attached to the discharge portion of the lubricator in order that the oil may be mixed with the graphite and steam before it passes from the lubricator.

40 Another object comprehended by this invention is the provision of a novel form of cutting mechanism for shaving the graphite from the solid stick, together with means for suitably supporting the shaving mechanism for reciprocatory movement, and means capable of attachment to a moving part of the engine being lubricated for reciprocating the cutting mechanism.

45 Other objects, such as the provision of means for holding the stick graphite in position to be engaged by the cutter and means for determining the quantity of graphite in the lubricator will appear and be more fully

described in the specification and illustrated in the accompanying drawings which form, 55 together with the appended claims, a clear disclosure of the invention.

In the drawings: Figure 1 is a central vertical longitudinal sectional view of the lubricator; Fig. 2 is a vertical sectional view 60 taken on the line 2—2 of Fig. 1; Fig. 3 is a fragmentary end elevation of the lubricator disclosing certain of the operating mechanism; Fig. 4 is a transverse sectional view taken on the line 4—4 of Fig. 2. Fig. 5 is 65 a fragmentary vertical sectional view, showing a somewhat modified form of structure; Fig. 6 is a fragmentary elevational view, showing a still further modified form of structure. 70

Corresponding and like parts are referred to in the following description and indicated in all the views of the drawings by the same reference characters.

Referring more specifically to Fig. 1 of 75 the drawings, it will be seen that the lubricator forming the subject matter of this invention includes a substantially cross-shaped body portion 10 which may be cast or otherwise formed as a single piece and from any 80 suitable metal or other material. The arms of this body portion are tubular in construction and the upper vertical arm 11 provides a chamber 12 adapted to receive a stick of graphite or other lubricant, being of cross 85 sectional shape and area to correspond to the cross sectional shape and area of the stick to be employed. This chamber is, however, preferably somewhat greater in cross sectional area than the stick of lubricant and, 90 at its lower end where it opens into the intermediate portion of the body is surrounded by an inwardly directed guide flange 13 which will snugly engage about the lower end of the stick of lubricant, which stick is 95 indicated by the numeral 14. The peripheral wall of the chamber 12 and also of the flange 13, is provided with a series of longitudinal leakage grooves or channels 15, best shown in Fig. 4, and the upper end of 100 the arm 11 is reduced and externally threaded to receive a cap 16, a packing ring 17 being preferably interposed between the cap and arm to form a tight joint. This cap 16 is formed centrally with an opening and 105 about this opening with an outwardly di-

rected threaded nipple 18. The stem 19 of a follower 20 extends through the opening in the cap 16 and the follower, which engages against the upper end of the graphite stick 14, is provided with a depending peripheral flange 21 surrounding such stick and guiding its upper end to keep the stick spaced from the wall of the chamber 12. Any suitable packing 22 is interposed in the 5 nipple 18 about the stem 19 and compressed by a threaded plug 23 which in turn is inclosed by an outer cap 24. This outer cap carries an indicating needle 25 which co-acts with a series of scale divisions 26 formed 10 upon the stem 19, whereby the amount of lubricant contained in the chamber 12 may be readily determined at a glance.

The arm 11 is provided at its lower end and at its upper end with tapped passages 20 27 and 28 by means of which steam may be admitted below the lower end of the graphite stick 14 and above the follower 20 in order that there will be an equal pressure of steam against both ends of the graphite stick, 25 whereby there will be no tendency toward motion upon the part of the stick, due to unbalanced steam pressure. To control the rate of feeding of the graphite, I provide one or more weights 29 in the form of disks 30 having radial slots to receive the stem 19 and adapted, when applied to the stem, to seat upon the follower 20.

The lower vertical arm 30 is in direct axial alignment with the arm 11, is also tubular 35 and is externally threaded at its lower end for threaded engagement in the wall of a steam chest or similar structure to which the lubricator is to be applied, a lock nut 31 being usually threaded upon the arm for 40 clamping engagement against the wall of the steam chest. Intermediate its length, the arm 30 is provided with an oil receiving opening 32 surrounded by a laterally extending nipple 33 adapted to be connected 45 directly to an oil cup or a pipe leading to a suitable source of oil supply.

The horizontally disposed arms 34 and 35 of the body 10 are also tubular and extend in axial alignment with each other, 50 each being externally threaded at its free end to receive an inner cap 36 formed centrally with an opening 37 and in spaced relation about this opening with an outwardly directed externally threaded nipple 38 55 adapted to receive an outer cap 39 which forces a clamping plug 40 into engagement with packing 41 positioned in the nipple 39 to form in effect a stuffing box construction. A shaft 42 which, as will be later 60 explained, partially supports and forms an actuating means for the cutting mechanism, is reciprocally mounted through the stuffing boxes thus provided, preferably extending through both stuffing boxes, as shown, 65 although one end of the arm 34 may be

closed and the shaft shortened to lie wholly within the lubricator at such end.

Secured to the shaft 42, by set screws 43 or other suitable means, are spaced brackets 44 which are connected to and support a carriage forming plate 45, the edges of which project into oppositely formed guide grooves or channels 46 in the walls of the arms 34 and 35. It will therefore be seen that these guide grooves prevent any turning movement of the plate 45 and that the brackets 44 connect this plate to the shaft 42 in such a manner that reciprocation of the shaft will cause reciprocation of the plate. The guide grooves 46 are so located and the brackets 44 so proportioned that the plate is positioned with its upper surface immediately adjacent the lower face of the peripheral flange 13 and, consequently, in such a position as to support the lower end of the graphite stick 14. The plate 45, intermediate its length, is provided with a pair of transversely extending spaced slots 46' and the portion of the plate defined between these slots has its edges upbent to form cutting edges 47 extending transversely of the plate and throughout the length of the opening between the walls of the flange 13. It will of course be understood that, if desired, the plate 45 may be merely formed with slots or perforations and a separate cutting blade, of any suitable type, may be secured to the upper face of the plate. The structure shown is, however, much simpler and more economical.

As a means for reciprocating the shaft 42, the arm 35 of the body is provided with a downwardly projecting ear 48 and a link 49 is pivotally connected at one end to the ear at its opposite end to the intermediate portion of a lever 50, the lever 50 being formed with a plurality of spaced pivot receiving openings 51 in order that the point of connection between the link and lever may be varied. The adjacent end of the shaft 42 is reduced and screw threaded, as shown at 52, to receive a clamping nut 53 secured in place by a set screw 54. Located between this nut 53 and the shoulder formed by reducing the shaft 42, is a sleeve 55 having trunnions 56 which engage in bearings formed in the arms of the forked terminal 57 of the lever 50. Washers 58 are preferably interposed between the ends of the sleeve 55 and the shoulder of the shaft and nut 53 to take up for wear. A link 59 is connected to the free end of the lever 50 and is adapted to be connected in any suitable manner to a moving part of a machine or other mechanism to be lubricated.

In describing the operation of the lubricator, it will be assumed, for the sake of clearness, that it is to be employed in lubricating the slide valve of a steam engine, although of course it may be employed for

other purposes with equal efficiency. When so employed, its arm 30 will be threaded into a tapped bore formed in the cap plate of the steam chest of the engine and the nut 5 31 turned home to tightly secure the lubricator in place. The link 59 will be connected to some suitable part of the engine, such as the valvestem and a pipe 50 will be led from any suitable source of steam supply and will 10 terminate in branches 61 and 62 communicating with the passages 27 and 28. Preferably, the pipe 60 will lead from the dry pipe between the throttle valve and engine cylinders so that when the engine is running 15 idly, there will be no steam admitted to the lubricator as there is, at that time, no occasion for utilizing a steam feed of the lubricant as the partial vacuum created by the cylinders will take care of the feed of 20 lubricant.

It will of course be clear that with the equalizing or leakage grooves 15, it is not absolutely essential that steam be supplied above the follower 29 through the branch 25 62 of the pipe 60 as steam may pass through these grooves into the space above the follower. On the other hand, it will be clear that if steam is supplied both above and below the graphite stick, the grooves are not 30 absolutely essential. However, it is better to provide both means for holding the graphite stick in place so that in case of failure of either one to operate properly, the other one may still prevent failure of the 35 device.

It will be clear that reciprocation of the valve stem will act through the link 59 and lever 50, the latter employing the link 49 as a fulcrum, to reciprocate the shaft 42 and, 40 consequently, cause the cutter blades 47 to pass back and forth across the lower face of the graphite stick and shave graphite therefrom. The steam entering through the pipe 60 will take up the graphite shavings thus 45 formed and drive them through the slot 46 and into the arm 30 of the lubricator and so to the part being lubricated. Oil may, of course, be supplied through the passage 32 to the mixed steam and graphite on its way 50 from the lubricator.

Although we have illustrated and described our invention in all its details, it will of course be understood that we do not wish to be limited to such details, as various 55 minor changes, within the scope of the appended claims, may be made, at any time, without in the slightest degree departing from the spirit of our invention. For instance, in place of using the weight 29 shown 60 in Fig. 1 of the drawings, the outer end of the stem 19 of the follower 20 may seat in a socket or bore formed in a weight 65 which is secured to the stem by a set bolt 66, this form of construction being illustrated in 65 Fig. 5 of the drawings.

In Fig. 6 of the drawings we have illustrated a construction by means of which the amount of graphite remaining in the lubricator may be read at a distance. This includes a suitable scale 67 located at any desired point and coöperating with the scale is an indicating needle 68 carried by one end of a cord 69 which is trained about suitable pulleys or rollers 70 and at its free end attached to a ring 71 carried by the upper 75 end of the stem 19. Various changes may also be made in the cutter mechanism, the latter being formed with two or more cutting edges, as deemed advisable.

Having thus described the invention, what 80 is claimed as new is:

1. A lubricator including a body member having vertically aligned tubular portions, one providing a graphite stick holding chamber and the other a lubricant passage 85 leading from the chamber, a reciprocably mounted cutter in the body member, movable across the lower end of the chamber, and means for holding the stick of graphite in engagement with the cutter. 90

2. A lubricator including a body member having vertically aligned tubular portions, one providing a graphite stick holding chamber and the other a lubricant passage leading from the chamber, a reciprocably 95 mounted cutter in the body member, movable across the lower end of the chamber, and means for holding the stick of graphite in engagement with the cutter, said means including means for indicating the amount 100 of graphite in the chamber.

3. A lubricator including a body having vertically aligned tubular portions, one providing a lubricant stick receiving chamber and the other a lubricant passage leading from the chamber, a cutter reciprocably mounted in the body and across the lower 105 end of the lubricant chamber and adapted to support a stick of lubricant therein, means for imparting reciprocatory movement to the cutter, and means for admitting steam to the lubricator above and below the lubricant therein. 110

4. A lubricator including a body having a chamber adapted to receive a stick of lubricant, the peripheral wall of said body being interiorly channeled longitudinally, a cutter mechanism reciprocably mounted in the body and forming a support for the lower end of the lubricant stick, and means 115 for admitting steam between the cutter and lubricant stick. 120

5. A lubricator including a substantially cross-shaped body having tubular arms, one of which is adapted for attachment to the 125 machine being lubricated and to provide a lubricant passage to such machine, a shaft reciprocably mounted in a pair of oppositely disposed arms, a cutter bearing plate carried by the shaft and extending across the lower 130

end of the other arm, and means in the other arm for forcing a stick of lubricant against the cutter carrying plate.

6. A lubricator including a substantially cross-shaped body having tubular arms, one of which is adapted for attachment to the machine being lubricated and to provide a lubricant passage to such machine, a shaft reciprocably mounted in a pair of oppositely disposed arms, a cutter bearing plate carried by the shaft and extending across the lower end of the other arm, and means in the other arm for forcing a stick of lubricant against the cutter carrying plate, and means for preventing swinging movement of the plate.

7. A lubricator including a substantially cross-shaped body having tubular arms, one of which is adapted for attachment to the machine being lubricated and to provide a lubricant passage to such machine, a shaft reciprocably mounted in a pair of oppositely disposed arms, a cutter bearing plate carried by the shaft and extending across the lower end of the other arm, and means in the other arm for forcing a stick of lubricant against the cutter carrying plate, the body being formed interiorly with grooves in which the edges of the plate seat.

8. A lubricator including a body providing a chamber adapted to receive a stick of lubricant, a shaft reciprocably mounted in

the body, a cutter mechanism carried by the shaft and adapted to shave lubricant from the stick upon reciprocating the shaft, and means adapted for attachment to a moving part of the machine for reciprocating the shaft.

9. A lubricator including a body providing a chamber adapted to receive a stick of lubricant, a shaft reciprocably mounted in the body, a cutter mechanism carried by the shaft and adapted to shave lubricant from the stick upon reciprocating the shaft, and means adapted for attachment to a moving part of the machine for reciprocating the shaft, said means being adjustable to vary the length of stroke of the shaft.

10. A lubricator including a body providing a chamber adapted to receive a stick of lubricant, a reciprocating shaft in the body, a plate carried by the shaft and forming a support for the lower end of the stick of lubricant, and cutter blades formed from the plate, said cutter blades being formed by the provision of spaced slots in the plate and the upturning of the edges of the strip defined by the slots.

In testimony whereof we affix our signatures.

EDWARD A. JONES. [L.S.]
JOHN E. JONES. [L.S.]
